UNITED STATES PATENT OFFICE.

GEORGE S. TALLERDAY, OF POUGHKEEPSIE, NEW YORK, ASSIGNOR TO QUEEN CITY KNITTING MILLS, INC., OF POUGHKEEPSIE, NEW YORK, A CORPORATION OF NEW YORK.

SHAWL.

1,157,341.

Specification of Letters Patent. Patented Oct. 19, 1915.

Application filed April 13, 1915. Serial No. 21,132.

To all whom it may concern:

Be it known that I, GEORGE S. TALLERDAY, citizen of the United States, residing at Poughkeepsie, in the county of Dutchess and State of New York, have invented certain new and useful Improvements in Shawls; and I do hereby declare the following to be a full, clear, and exact description of the invention, such as will enable others skilled in the art to which it appertains to make and use the same.

My invention consists in the novel features hereinafter described, reference being had to the accompanying drawing which shows one embodiment of my invention which I have selected for purposes of illustration, and the said invention is fully disclosed in the following description and claims.

Referring to the said drawing, Figure 1 represents a perspective view of my improved shawl as worn upon the person. Fig. 2 is a perspective view of the shawl detached from the wearer and showing the same opened and ready to be donned by the wearer. Fig. 3 is a similar view showing the shawl closed. Fig. 4 is a sectional view taken on line 4—4 of Fig. 3. Fig. 5 is a similar view taken on line 5—5 of Fig. 3.

My invention relates primarily to ladies' shawls or scarfs although it is also applicable to other purpose, the object being to provide a shawl or scarf which will retain its position on the shoulders without the necessity of the employment of any extraneous fastening device.

A further object of my invention is to provide an improved shawl or scarf which is adapted to cover the shoulders, arms, and a portion of the back of the wearer, and which after being placed on the wearer will snugly engage those portions of the body with which it contacts.

According to my invention, I attach to or form integrally with the shawl or scarf, 45 short sleeves or the equivalent, comprising a wristlet provided at each end of said shawl.

In carrying out the invention I proceed as follows, that is to say, I provide a shawl which is folded centrally and longitudinally to form opposite sides which are left unsecured at their free edges except at the ends of the shawl which terminate in bands or wristlets.

As above stated the wristlets are formed

integrally with the shawl, that is to say, formed in the process of knitting by which the shawl may be made.

In the drawings 1 designates the main or body portion of my improved shawl which is preferably made of knitted fabric and by the process of knitting and is preferably approximately oblong in shape or of a length sufficient to reach from one of the wearer's wrists over the shoulders and around the back to the other wrist. This body portion is preferably folded centrally and longitudinally along the line 2, to form opposite sides 3 and 4 which when placed on the wearer, are adapted to snugly engage the shoulders, arms and a portion of the back. The ends of the body portion 1 are connected or made integral with tubular wristlets 5 and said ends are reduced in width in order to neatly connect with the wristlets, as shown at 6.

In donning the shawl, the hands of the wearer are first placed through the wristlets and the hands are then raised and the body portion 1 of the shawl thrown over the head to engage the shoulders. The shawl will then form a semi-coat or short coat in which the sleeves are left open on the underside, as shown at 7. My device in effect forms a short jacket in which the sleeves are integral with the body and need not be separately applied.

Scarfs or shawls made as above described, are found to retain their place on the shoulders of the wearer without any tendency to fall, the wristlets exerting the necessary grip without any discomfort, and owing to the fact that no extraneous fastenings are needed, the life of the garment is prolonged.

It is obvious that while I have shown my improved shawl as made of knitted fabric, it can be constructed of any desired material and in any suitable manner. For example, either side of the shawl 2 or 3 might be reduced or extended laterally for the purpose of covering more or less of the wearer's body.

What I claim and desire to secure by Letters Patent is:—

1. A scarf or shawl comprising a body portion of the same width, throughout substantially its entire length, adapted to cover the shoulders and the upper portion of the back, and provided at its extremities with means for engaging the wearer's wrists.

2. A scarf or shawl comprising a body

portion narrower at its extremities than at its central portion, adapted to cover the shoulders and the upper portion of the back, and provided at its extremities with means 5 for engaging the wearer's wrists.

3. A scarf or shawl comprising a body portion adapted to cover the shoulders and back of the wearer, the longitudinal edges of which are unsecured except at a portion 10 of their length toward their extremities, where they are secured together.

4. A scarf or shawl comprising a body portion approximately rectangular in shape and adapted to cover the shoulders and the 15 upper portion of the wearer's back and provided at its extremities with tubular portions to be engaged by the wrists of the wearer.

5. A scarf or shawl comprising a body

portion approximately rectangular in shape 20 and folded upon itself to form opposite side portions, the free edges of which are unsecured except at a portion of their length adjacent their extremities, where they are secured together.

6. A scarf or shawl comprising a body portion approximately rectangular in shape and folded longitudinally upon itself to form opposite side portions, the free edges of which are unsecured, and integral tubular 30 portions provided at the extremities of the body portion.

In testimony whereof I affix my signature, in the presence of two witnesses.

GEORGE S. TALLERDAY.
